UNITED STATES PATENT OFFICE.

JOHN A. HOWARD, SR., OF WEST NEW BRIGHTON, NEW YORK, ASSIGNOR TO THE
CAMWARD ENGINEERING CO. INC., A CORPORATION OF NEW YORK.

ADJUSTABLE REST FOR WASHBOARDS.

1,377,076.

Specification of Letters Patent.

Patented May 3, 1921.

Application filed May 28, 1920. Serial No. 384,978.

To all whom it may concern:

Be it known that I, JOHN A. HOWARD, Sr., a citizen of the United States, residing at West New Brighton, S. I., in the county of 5 Richmond and State of New York, have invented new and useful Improvements in Adjustable Rests for Washboards, of which the following is a specification.

This invention relates to adjustable rests 10 for wash boards, and the principal object is to provide means whereby a standard wash board may be held in any of a plurality of positions so as to accommodate it to use by tall and short people and to adjust the 15 angularity of the board to suit the wishes of the individual using it.

Another object is to provide such a device which may be readily removed from or attached to the side of the tub.

20 Other objects will appear from the following description.

One embodiment of my device is illustrated in the accompanying drawing consisting of one sheet, in which:—

25 Figure 1 is a side elevation of a wash tub supporting a wash board by means of my improved device.

Figs. 2, 3 and 4 are similar views showing the board in a variety of positions.

30 Fig. 5 is an enlarged detail view of one of the supporting members.

Like characters of reference refer to like parts in all of the views.

This invention contemplates the providing 35 of a pair of rests with means for supporting them from the side of the tub, said rests being formed so as to be capable of supporting a wash board in a plurality of angular positions and at a plurality of vertical heights.

Referring more particularly to the drawings, 1 represents an ordinary wash tub and 2 a wash board of any ordinary and well-known make provided with the side strips 3.

40 The rest members are represented at 4, and I provide two of these, one for engagement with each of the side strips 3 of the wash board. Each of these rests comprises

a single curved member shaped so as to touch the tub with the points 5, 6 and 7 50 whereby it is securely supported by said tub. Each rest has a curvilinear face 8 against which the wash board may be firmly secured by a lag-screw 9 or similar device which may be passed through any one of a plurality of holes 10 bored in the rest and screwed into the member 3 of the wash board. 55

If desired an additional securing means may be provided in the form of a hook member 11 adapted to co-act with a number 60 of nails or like elements 12 on the sides of the wash board.

It will be readily understood that by putting the screw 9 through different ones of the holes 10 different angles of inclinations 65 may be obtained from the wash board, while by raising or lowering the board and then screwing in screw 9, the board may be supported at different heights so as to render it suitable for tall and short persons. 70

While I have described what I consider to be the most desirable embodiment of my invention, it is obvious that many of the details may be varied without in any way departing from the spirit of my invention; 75 and I, therefore, do not limit myself to the exact details of construction herein set forth nor to anything less than the whole of my invention limited only by the appended claim. 80

What I claim as new and desire to secure by Letters Patent is:—

In a device of the class described, the combination with a wash-board of a pair of substantially C-shaped supports adapted to 85 hook on the side of a tub and provided with a plurality of apertures through them, screws adapted to be passed through said apertures and to be seated in the frame-work of said wash-board to secure the latter in 90 place, eyes on said wash-board, and a hook on each of said supports adapted to be engaged with respective ones of said eyes.

In testimony whereof I have affixed my signature.

JOHN A. HOWARD, Sr.
